[57] CLAIM

The ornamental design for a wind deflector for vehicles, as shown and described.

DESCRIPTION

FIG. 1 is a front perspective view of a wind deflector for vehicles showing a first embodiment of my new design;

FIG. 2 is a side elevational view of the deflector, the opposite side being a mirror image thereof;

FIG. 3 is a front elevational view thereof;

FIG. 4 is a top plan view thereof;

FIG. 5 is a rear elevational view thereof;

FIG. 6 is a bottom plan view thereof;

FIG. 7 is a rear elevational view of a wind deflector for a vehicle showing a second embodiment of my new design;

FIG. 8 is a front elevational view of the second embodiment; and

FIG. 9 is an exploded front isometric view of the second embodiment with the fastening member omitted for convenience of illustration.

FIG. 1

FIG. 2

FIG. 3
